(57) **CLAIM**

The ornamental design for a cap for post anchor as shown and described.

DESCRIPTION

FIG. 1 is a perspective view of a first embodiment of a cap for post anchor;

FIG. 2 is another perspective view thereof;

FIG. 3 is a front view thereof;

FIG. 4 is a right side view thereof;

FIG. 5 is a top view thereof;

FIG. 6 is a rear view thereof;

FIG. 7 is a left side view thereof;

FIG. 8 is a bottom view thereof;

FIG. 9 is a cross-section taken in the plane of line 9-9 of FIG. 1, a cross-section taken in the same plane but looking in an opposite direction being a mirror image of FIG. 9;

FIG. 10 is a perspective of a second embodiment of a cap for post anchor;

FIG. 11 is another perspective view thereof;

FIG. 12 is a front view thereof;

FIG. 13 is a right side view thereof;

FIG. 14 is a top view thereof;

FIG. 15 is a rear view thereof;

FIG. 16 is a left side view thereof;

FIG. 17 is a bottom view thereof;

FIG. 18 is a perspective view of a third embodiment of a cap for post anchor;

FIG. 19 is another perspective view thereof;

FIG. 20 is a front view thereof;

FIG. 21 is a right side view thereof;

FIG. 22 is a top view thereof;

FIG. 23 is a rear view thereof;

FIG. 24 is a left side view thereof;

FIG. 25 is a bottom view thereof;

FIG. 26 is a cross-section taken in the plane of line 26-26 of FIG. 18, a cross-section taken in the same plane but looking in an opposite direction being a mirror image thereof;

FIG. 27 is a perspective view of a fourth embodiment of a cap for post anchor;

FIG. 28 is another perspective view thereof;

FIG. 29 is a front view thereof;

FIG. 30 is a right side view thereof;

(Continued)

FIG. 31 is a top view thereof;

FIG. 32 is a rear view thereof;

FIG. 33 is a left side view thereof; and,

FIG. 34 is a bottom view thereof.

The broken lines in a dot-dash pattern indicate boundary lines between claimed and unclaimed portions of the sleeve. The broken lines in a dash-dash pattern indicate portions of the cap for post anchor that form no part of the claimed design.
